CLAIM

The ornamental design for a vehicle front upper bumper fascia, as shown and described.

DESCRIPTION

FIG. 1 is a perspective view of the vehicle front upper bumper fascia;

FIG. 2 is a front view thereof;

FIG. 3 is a right side view thereof (where the left side view is omitted since the left side view is substantially a mirror image of the right side view); and,

FIG. 4 is a top view thereof.

The broken lines shown in the drawings depict portions of the vehicle front upper bumper fascia that form no part of the claimed design.
